Primary Examiner — Jonathan J Han(74) *Attorney, Agent, or Firm* — Shen Huang**CLAIM**

The ornamental design for a shoe, as shown and described.

DESCRIPTION

FIG. 1 is a first perspective view of a shoe showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines and the area within the broken lines in the drawings depict portions of the shoe that form no part of the claimed design.

1 Claim, 8 Drawing Sheets(56)
